SHIPPING CONTAINER WITH PROVISION
FOR PROTECTING CORNERS OF CON-
TENTS

Samuel Stimmel, Bronx, N. Y.

Application June 19, 1948, Serial No. 33,978

5 Claims. (Cl. 229—87)

1

This invention relates to shipping containers or folders such as are made of corrugated paperboard, and the invention relates more particularly to a construction of a shipping folder with special provisions for protecting the corners of the contents against damage during shipment.

When shipping electro-plates or lithographed displays, the greatest danger of damage during shipment is that one or more corners of the plate or display may be bent or crushed as a result of someone dropping the shipping container on its corner when handling during transit. Various constructions for shipping containers have been devised, and those which have effectively protected their contents have often been unnecessarily expensive because of the large number of flaps and panels used, or have been expensive to use because of the unreasonable time required for packing, closing and sealing them. The container of this invention requires less material to manufacture and this results in a saving both in manufacturing and in the postage used for shipping.

It is an object of this invention to provide an improved shipping container using a minimum of corrugated paperboard for effectively protecting a shipping item, such as, a flat plate or display, from damage in shipment.

One feature of the invention relates to a one-piece container having a panel with its ends folded over to prevent endwise displacement of the contents of the container, and with side flaps that enclose the contents and that are hinged to the panel, preferably at regions inward from the folded ends so that the folded ends extend beyond the corners of the actual space that houses the plate or other item enclosed within the container.

Other objects, features and advantages of the invention will appear or be pointed out as the description proceeds.

In the drawing, forming a part hereof, in which like reference characters indicate corresponding parts in all the views,

Fig. 1 is a top plan view of a shipping container embodying this invention with the flaps shown in open positions.

Fig. 2 is an enlarged view, partly broken away, taken along the line 2—2 of Fig. 1.

Fig. 3 is a sectional view along the line 3—3 of Fig. 1 but with the flaps raised and moved part way toward closed position.

Fig. 4 is a greatly enlarged, fragmentary view taken along the line 4—4 but with the left hand flap of the container in closed position,

2

Fig. 5 is a reduced scale, plan view of an outside box that can be used to enclose the container shown in Figs. 1 to 4.

Fig. 6 is a top plan view showing the box of Fig. 5 when closed.

Fig. 1 shows a one-piece folder or shipping container, preferably made of corrugated paperboard, and having a main panel 10 with end portions 11 and 12 formed by folding over the ends 10 of the material in the manner shown in Fig. 2.

The terms "fold" or "folded," as used in this specification and in the claims, denote a construction in which the material is turned back in a bend of 180 degrees and its marginal edge 15 is tucked into the space within the bend as shown in Fig. 2. The top layer of the fold need not contact with the marginal edge beneath it.

The folded end portions 11 and 12 are permanently held in their folded condition by fastening means, preferably staples 14. With this construction, the folded end portions 11 and 12 provide cushions or abutments at opposite ends of the main panel 10 for stopping endwise movement of a shipping item that is placed on the panel 10. The height of these abutments is equal to at least twice the thickness of the corrugated paperboard of which the folder is made, or may be of greater height if the top layer of the fold 25 is spaced from the tucked in marginal edge. When such spacing is considerable, only the middle layer edge portion and the main panel are clamped together by the staples 14.

The folder has side flaps 16 and 17 hinged to the opposite sides of the panel 10 along parallel creases 19 and 20. In the preferred construction, the spacing of each of the creases 19 from the adjacent crease 20 is less than the height of the folded end portions 11 and 12 so that when the flaps 16 and 17 are swung inward to positions 30 parallel with the top surface of the panel 10, the space between the top surface of the panel 10 and the overlying surfaces of the flaps 16 and 17 is completely closed at both ends by the folded end portions 11 and 12. In the preferred construction, the creases 19 and 20 are close enough together to cause the top surface of the flaps 16 and 17 to be no higher than the top surfaces of the end portions 11 and 12 when the flaps 16 and 17 are swung inward over the panel 20. Fig. 4 35 shows the panel 16 in such a position and at a level somewhat below the top surface of the end portion 11. A shipping item 21 is shown in dotted lines. If a higher shipping item is enclosed in the folder, the flap 16 can be bent over the shipping item along a line above the crease 19 so as

to increase the size of the space within the folder without affecting the folded end portion 11.

The corrugations of the paperboard of which the folder is made preferably extend lengthwise of the panel 10 so that the creases 19 and 20 are along the corrugations. This means that the creases of the folded end portions 11 and 12 must extend transversely of the corrugations of the paperboard, but the creases of the end portions 11 and 12 are only bent once and are held in their bent conditions by the staples 14. The creases 19 and 20, on the other hand, are flexed many times when the folder is packed and unpacked during repeated use, and it is important that these creases extend along the corrugations so that the hinges provided by the creases can be used repeatedly without damaging the paperboard.

The flaps 16 and 17 are preferably wide enough so that each of them covers substantially one-half of the panel 10 when the flaps are swung inward over the panel. By having these flaps substantially meet over the center of the panel 10, the folder shown in Fig. 1 is suitable as a shipping container because it completely encloses an electroplate, lithographed display, or other shipping item that is placed on the panel 10 before the flaps 16 and 17 are swung inward to close the folder or container. A sealing strip can be placed over the seam between the confronting edges of the flaps 16 and 17 when the flaps are in closed position.

It is a feature of the preferred construction that the creases 20 are spaced inward from the sides of the folded end portions 11 and 12. In the construction illustrated, the creases 19 are also spaced inward from the sides of the folded end portions 11 and 12, but this is not essential. It is merely necessary that the folded end portions extend beyond the hinged connections between the panel 10 and the flaps 16 and 17 when the flaps are swung inward to close the folder.

This construction provides a very effective protection for the corners of the space in which the shipping item is enclosed. The folded end portions 11 and 12 extend beyond the corners of the enclosed space both lengthwise and sideways, and provide a triple thickness of corrugated paperboard which resists crushing or deformation of the folder if it drops on one corner. Such a dropping on the corner of the container is the type of blow most likely to cause injury to a shipping item having square corners, and against such injury the container of this invention provides adequate protection. The staples 14 located reasonably close to the sides of the end portions 11 and 12 provide further strength by tying layers of the corrugated paperboard together.

The shipping folders of this invention can be used for shipping a stack of plates or sheets, and the height of the space enclosed by the folder can be increased by spacing the creases 19 and 20 further apart, and by increasing the height of the folded end portions 11 and 12. Such an increase in height can be obtained by using thicker material for the container, by doubling the margins of the end portions 11 and 12 back on themselves one or more times, or by spacing the top of the fold further from the tucked in marginal edge portion that is stapled to the main panel 10.

For containers that are to be used for stacks of substantial height, it is sometimes desirable to use thicker corrugated paperboard because an increase in the weight of the contents ordinarily requires a thicker corrugated board for

adequate protection over the broad expanse of the top and bottom surfaces of the folder. It will be understood, of course, that while this container is primarily intended for protecting articles having corners, it can be used also for shipping items of other shapes such as disk records used for phonographs.

Fig. 5 shows an outside box that is combined with the folder of Figs. 1 to 4 when articles are to be shipped under conditions that make additional layers of corrugated paperboard desirable to provide adequate insurance against breakage. This box, indicated generally by the reference character 25, comprises a main body panel 26 with flaps 27 and 28 hinged to its opposite ends by creases 29 and 30. The main body panel 26 also has side flaps 32 and 33 hinged to its opposite sides by creases 35 and 36.

The length of the body panel 25 is substantially equal to or slightly longer than the length of the folder panel 10 including its end portions 11 and 12. The width of the body panel 26 is substantially equal to, or slightly greater than, the width of the end portions 11 and 12 of the folder. The distance between the creases 29 and 30 is at least as great as the height of the end portions 11 and 12; and the creases 35 and 36 are somewhat further apart than the creases 29 and 30 so that when the flaps 27 and 28 are swung in over the end portions 11 and 12 of the folder, the flaps 31 and 32 can be swung into closed positions overlying the closed flaps 28 and 29, and substantially parallel to the body panel 26.

Fig. 6 shows the box 25 in its closed condition. Before shipment, the box 25 ordinarily has a sealing strip glued over the seam between the confronting edges of the flaps 32 and 33. This sealing strip is passed around the ends of the box and along the outside surface of the body panel 26 of the box so that the sealing strip not only closes the seam between the flaps 32 and 33, but also holds these flaps down against the end flaps 27 and 28 so that the box cannot open during shipment.

When the folder is to be enclosed in the box 25, the folder need not have such wide flaps 16 and 17 because any gap between the confronting edges of these flaps 16 and 11, when closed, is covered by the box 25. When the folder is made with narrow flaps 16 and 17, they are held closed by running a sealing strip around the girth of the folder.

The preferred embodiment of this invention has been illustrated and described, but changes and modifications can be made, and some features can be used alone or in different combinations without departing from the invention as defined in the claims.

What is claimed is:

1. A one-piece shipping container comprising a corrugated paperboard panel with end portions folded upward and inward, means holding said end portions in their folded condition so as to form an abutment at both ends of the top surface of the panel for preventing endwise displacement of an article resting on the panel, flaps connected with opposite sides of the panel, each of said flaps being hinged to the panel along parallel creases on which the flap swings inward over the panel to hold an article against the panel and to prevent transverse displacement of the article, at least the inner of said creases being spaced from the sides of the folded end portions 75 of the panel so that the folded end portions ex-

tend beyond the corners of the space within which the article is confined.

2. A corrugated paperboard folder comprising a panel in which the corrugations extend lengthwise of the panel, end portions on opposite ends of the panel folded over against the top surface of the panel along creases extending transversely of the corrugations of the paperboard, flaps connected to the opposite sides of the panel between the folded end portions of the panel along creases that are parallel to the corrugations of the paperboard and that are spaced inward from the sides of the folded over end portions of the panel.

3. The combination of a one-piece folding box having a body panel and flaps hinged to the opposite ends and opposite sides of said body panel along creases on which two of the flaps fold inward parallel to the body panel and at a predetermined distance above the surface of the body panel, and along which the other two flaps fold inward over the first two flaps to close the box, and a folder having a panel with folded over end portions, the combined length of said panel and its folded end portions being substantially equal to that of the body panel of the box, and the height of the folded end portions of the panel being substantially equal to said predetermined distance between the body panel and the overlapping parallel flap of the box, and the width of the folded over end portions of the end panel being substantially equal to the width of the body panel of the box, and flaps connected to opposite sides of the panel along lines spaced inward from the sides of the folded end portions of the panel and extending inward over the top surface of the panel to enclose a shipping item located on the panel.

4. A one-piece shipping container comprising

5 a corrugated paperboard panel with end portions that hinge upward and inward to form abutments at both ends of the top surface of the panel for preventing endwise displacement of an article resting on the panel, flaps connected with opposite sides of the panel, said flaps being hinged to the panel along creases on which the flaps swing inward over the panel to hold an article against the panel and to prevent transverse displacement of the article, said creases being spaced inwardly from the sides of the abutments formed by said end portions of the panel so that the end portions project transversely of the creases and laterally beyond the same to provide corner abutments.

10 6 5. A corrugated paperboard folder comprising a panel, end portions on opposite ends of the panel creased to fold over the top surface of the panel along creases extending transversely of the panel to form abutments for preventing endwise movement of an article in the folder, flaps connected to the opposite sides of the panel between the abutments formed by said end portions of the panel along creases that are spaced inward from the sides of the folded over end portions of the panel.
